UNITED STATES PATENT OFFICE.

BERNARD T. LEVEQUE, OF WENHAM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DRIVING AND STOPPING MECHANISM.

Application filed November 12, 1917. Serial No. 201,542.

To all whom it may concern:

Be it known that I, BERNARD T. LEVEQUE, a citizen of the United States, residing at Wenham, in the county of Essex and State 5 of Massachusetts, have invented certain new and useful Improvements in Driving and Stopping Mechanism; and I do hereby declare the following to be a full, clear, and exact description of the invention, such as will 10 enable others skilled in the art to which it appertains to make and use the same.

The invention relates to driving and stopping mechanism adapted for use in sewing or other machines which are to be stopped 15 with the parts in a predetermined position when the driving power is thrown off.

The object of the invention is to provide a novel and improved mechanism which will enable the operator to readily throw the 20 stopping devices out of active position without throwing on the power, in case he desires to turn the driving shaft by hand, and will also enable him to throw the power off while the stopping devices remain inactive, 25 in case movement of the driven parts is arrested during their operation in such position that the return of the stopping devices to active position is prevented.

To this end the invention contemplates so 30 connecting the power throw-off and stopping devices that while they normally move together yet either may be moved independently in case the other is held from movement. These parts are preferably thus connected by 35 a spring which will yield to allow the stopping devices to be independently moved into inactive or stopping position while the power throw-off devices are retained in stopping position, or which will yield to allow the 40 power throw-off devices to be independently moved in a direction to throw off the power when the simultaneous movement of the stopping devices into stopping position, which would normally take place, is prevented. The 45 invention also contemplates the provision of a device which may be manipulated by the operator either to retain the power throw-off devices in stopping position when the stopping devices are to be independently moved into 50 starting position, or to move the power throw-off devices into stopping position when the driven parts are stopped, as by jamming of the operating parts of the machine, in such position that movement of the

stopping devices into stopping position is 55 prevented. This device is preferably a manually operable cam arranged to hold the power shifter in or to move it into stopping position when operated by the operator.

In addition to the features outlined above, 60 the invention includes certain further features of construction and combinations of parts which will be hereinafter described and set forth in the claims.

The various features of the invention will 65 be readily understood from an inspection of the accompanying drawings and the following detailed description of the mechanism illustrated therein.

In the drawings, Figure 1 is a sectional elevation on line 1, Fig. 3; Fig. 2 is a detail partly in section on line 2, Fig. 1; Fig. 3 is a sectional plan view on line 3, Fig. 4; Fig. 4 is a sectional view on line 4, Fig. 3; Fig. 5 is a sectional detail on line 5, Fig. 3; and Figs. 70 6 and 7 are similar views showing the parts 75 in different positions.

In the drawings the invention is shown embodied in a button sewing machine the operating parts of which are mounted in a 80 frame 2 which is pivoted at 4 on a base 6. The various parts of the machine are operated from a cam shaft 8 which makes one revolution for each cycle of the machine. This shaft is driven through mechanism 85 which is thrown into operation by manually controlled means such as a treadle, and which, upon the release or shifting of the treadle, operates to stop the shaft and therefore the parts of the machine in a predetermined position. As shown, the cam shaft 8 is driven from a driving shaft 10 through gearing which is so proportioned that the cam shaft makes one revolution every four revolutions of the driving shaft. The driving shaft carries a driving pulley 12 and a stop cam 14 which is provided with an eccentric braking portion 16 and a stopping depression 18. The driving pulley is arranged adjacent to a loose pulley 20 mounted on a shaft in the base of the machine which is in line with the driving shaft 10. The driving shaft is driven through a belt 22 which is shifted from one pulley to the other in throwing the power on and off. When the belt is shifted on to the loose pulley to throw off the power the shaft is stopped in a predetermined position by a stop 95 100 105

pin 24 which is arranged to ride on the periphery of the stop cam, and is carried upon an arm 26 secured to a shaft 28. The shaft is pressed in a direction to force the end of the stop pin against the periphery of the stop cam by a spring 30. The pin is moved laterally into and out of the path of the stop cam by a forked arm 32 which is secured to a rock shaft 34 and embraces the end of the arm 26. The rock shaft is forced yieldingly in a direction to bring the stop pin into the path of the cam by a torsional spring 36. The rock shaft is moved in the opposite direction to disengage the stop pin from the cam through a link 38 connecting the arm 32 with one arm of a bell crank lever 40, the other arm of which is connected by a rod 42 with an operating treadle. The movement of the rock shaft 34 also operates the belt shifter 44. The belt shifter is secured in the upper end of an arm 46 which is loosely mounted on the shaft 34, and is connected to move in unison with the shaft by a spring 48 and a pin 50 which projects from the hub of the arm into a recess 51 formed in the adjacent end of a sleeve 52 secured to the shaft. One end of the spring is connected to the hub of the arm 46 and the other is connected to the sleeve 52. The spring normally holds the pin in engagement with one side of the recess as indicated in Fig. 5, so that the belt shifter arm will move with the rock shaft 34 when this shaft is rocked to move the stop pin into or out of stopping position. This connection, however, permits the shaft to be rocked to move the stop pin into inactive or starting position while the belt shifter is retained in stopping position with the belt on the loose pulley as indicated in Fig. 7, and also permits the belt shifter to be moved to shift the belt from the driving pulley to the loose pulley while the shaft is retained in position with the stop pin in starting or running position out of the path of the stop cam.

The means for retaining the driving belt on the loose pulley while the stop pin is moved laterally out of the path of the stop cam, in case it is desired to turn the driving shaft by hand, comprises a cam 54 secured to the inner end of a rock shaft 56, the outer end of which carries an operating handle 58. The cam 54 is in the form of a flange projecting from a sleeve secured to the rock shaft, and arranged to engage a lug 60 on the rear side of the belt shifter. When the cam is in the position indicated in Figs. 3, 5 and 6, the flange is out of the path of the lug 60, and the belt shifter is free to move with the rock shaft 34 when it is rocked in starting or stopping the machine. If the parts are in stopped position indicated in Figs. 3 and 5, and the cam 54 is moved into the position indicated in Fig. 7, it will engage the lug 60 on the belt shifter, and re-

tain the belt shifter in this position when the shaft 34 is rocked to move the stop pin into inactive or starting position out of the path of the stop cam. The machine may then be turned by hand, and to enable this to be conveniently done a shaft 62 is connected with the cam shaft through a pinion 64, and is provided on its outer end with a hand wheel 66. In case the machine stops during its operation, with the parts out of stopping position, the driving belt may be shifted on to the loose pulley while the stop pin remains in running position by turning the cam into the position indicated in Fig. 7, thus enabling the cam shaft to be turned back or manipulated in restoring running conditions.

In order that the cam shaft may be automatically stopped in a predetermined position by the action of the stop cam on the driving shaft, the cam shaft is provided with a cam surface 68 arranged to engage a roll 70 on the bell crank 40, and provided with a recess 72 which registers with the roll during a part of every fourth revolution of the driving shaft.

In order that the tension may be released when the machine stops, or when the stopping devices are moved into inactive position for hand manipulation of the machine, an arm 74 is connected with the bell crank lever 40, and is arranged to engage one arm of a lever 76, the other arm of which is arranged to pass between the discs 78 of the tension, as indicated in Figs. 1 and 2.

While it is preferred to employ the specific construction and arrangement of parts shown and described in embodying the invention in the sewing machine indicated in the drawings, it will be understood that this construction and arrangement is not essential to the broader features of the invention, but may be varied or modified as found desirable or best suited to the mechanism in which the invention is to be embodied.

Having explained the nature and object of the invention, and specifically described one form of mechanism in which it may be embodied, what is claimed is:—

1. Driving and stopping mechanism having, in combination, power shifting devices, stopping devices, a yielding connection between the said devices for causing them to normally operate in unison and arranged to permit independent movement of either out of active position when the normal accompanying movement of the other is prevented.

2. Driving and stopping mechanism, having, in combination, power shifting and stopping devices, a spring connecting the devices to cause them to normally operate in unison and arranged to yield to permit independent movement of one out of active position when the normal accompanying movement of the other is prevented.

3. Driving and stopping mechanism, having, in combination, power shifting and stopping devices means connecting the devices to normally operate in unison and to 5 permit independent movement of either when movement of the other is prevented, and manually operable means for retaining the power shifting device in or moving it into stopping position.
- 10 4. Driving and stopping mechanism, having, in combination, power shifting and stopping devices, a spring connecting the devices to cause them to normally operate in unison and yielding to permit independent 15 movement of the stopping device into starting position, and a manually operable means for retaining the power shifter in stopping position.
5. Driving and stopping mechanism, having, in combination, power shifting and stopping devices, a spring connecting the devices to cause them to normally operate in unison and to permit independent movement of the stopping device into starting 20 position, or independent movement of the power shifting device into stopping position, and manually operable means for retaining the power shifting device in or moving it into stopping position.
- 25 6. Driving and stopping mechanism, having, in combination, a shaft, a stop cam on the shaft, a yielding stop pin, actuating means for shifting the pin into and out of register with the cam, a power shifter, and connections between the shifter and actuating means including a spring arranged to 30
- yield to permit independent movement of the pin out of register with the cam.
7. Driving and stopping mechanism, having, in combination, a shaft, a stop cam on the shaft, a yielding stop pin, an actuating shaft connected to move the pin laterally into and out of register with the cam, a power shifter, a connection between the shaft and shifter permitting lost motion, 40 and a spring normally preventing said lost motion.
8. A driving and stopping mechanism having, in combination, power shifting and stopping devices, a spring connecting the devices to cause them to normally move in unison in starting the driven parts, mechanism included in the driven parts for retaining the stopping devices in inactive 45 and the power shifting devices in active position during a part of the driving interval, and means for manually moving the power shifting devices into inactive position in case the driven parts stop during the active 50 interval of said mechanism.
9. A driving and stopping mechanism having, in combination, power shifting and stopping devices, means for manually moving the stopping devices into starting position, a spring through which said means 55 also moves the power shifting devices into driving position, and means which may be set by the operator to retain the power shifting devices in stopping position while the stopping devices are moved into inactive 60 position against the tension of the spring.

BERNARD T. LEVEQUE.
